UNITED STATES PATENT OFFICE.

WILLIAM DIETER, OF NEW YORK, N. Y., ASSIGNOR TO E. W. BLISS COMPANY, OF BROOKLYN, NEW YORK, A CORPORATION OF WEST VIRGINIA.

REDUCING-VALVE FOR AUTOMOBILE TORPEDOES.

1,136,660.

Specification of Letters Patent. Patented Apr. 20, 1915.

Application filed April 15, 1913. Serial No. 761,293.

To all whom it may concern:

Be it known that I, WILLIAM DIETER, a citizen of the United States, residing in the borough of Brooklyn, county of Kings, city and State of New York, have invented certain new and useful Improvements in Reducing-Valves for Automobile Torpedoes, of which the following is a specification.

In the modern automobile torpedo, compressed air is stored in the reservoir or air flask at a pressure of at least 2250 pounds per square inch; this air is confined by a starting valve which opens automatically during the launching, thereby admitting the high pressure air to a reducing valve which reduces its pressure to approximately from 400 to 600 pounds per square inch (depending upon the speed for which the torpedo is set); the air at this reduced pressure is conducted through a heater (technically called a superheater), in which a fierce combustion is maintained during the run by the burning of alcohol or other fluid combustible therein, accompanied by a spray of water which is converted into steam, so that the steam and products of combustion add greatly to the volume of the motive fluid, and increase greatly the power exerted by compressed air alone; this fluid is conducted from the superheater to the engine, which in the Bliss-Leavitt torpedo is a turbine. The reducing valve requires to have great strength because of the high pressure admitted to it, and it requires a high degree of sensitiveness in order that the air delivered from it may be held as nearly as possible at the predetermined pressure during the entire period of the run. A difficulty is involved in that while the initial air pressure exceeds 2200 pounds, this pressure progressively diminishes during the run, until toward the end of the run it may fall below 600 pounds. It has been found impossible to construct and adjust a pressure regulator which is adaptable to these extreme conditions, and which can maintain an ideal uniformity of pressure on the discharge side. An obvious remedy for this difficulty which has been repeatedly suggested for years past, is the resort to dual or multiple stage reduction; that is to say, the provision of a primary reducing valve for dealing with the high pressures, and a secondary (or even a tertiary) valve of greater sensitiveness for effecting the final reduction. This expedient has been

successfully adopted in other arts where it is necessary to accomplish a reduction from an excessively high pressure to a very low pressure, and where it was requisite to maintain the final pressure at an ideal approach to uniformity. A familiar example is the well known Pintsch gas system so largely used on railways. To apply such a dual stage reduction to the requirements of a torpedo, would involve that the primary valve should drop the varying pressure from the air flask to an approximately uniform pressure in the neighborhood of said 600 to 700 pounds; while the secondary valve would effect the relatively slight reduction 70 from this pressure to the final pressure of say 500 to 400 pounds, varying according to the speed for which the torpedo is set. The adoption of this dual reduction scheme has however been prevented by what has heretofore proved an insuperable obstacle, namely, that the torpedo was already crowded so full of mechanism that the addition of any further instrumentalities would be impracticable without increasing its size. Equally 80 the addition of any material further weight would be impracticable without changing the displacement of the torpedo. Inasmuch as the size and weight have for each type or make of torpedo become standard, any 85 change in these respects would involve disadvantages far more serious than the comparatively trifling defect of the single valve reduction. The present invention, however, is believed to provide a practicable means 90 for applying the two-stage principle of pressure reduction without involving any material increase in the size or weight of the reducing instrumentalities.

The improvement introduced by this invention will be made apparent from the description of the accompanying drawings, wherein,—

Figure 1 is a diagrammatic view illustrating an imaginary arrangement of the reducing mechanism and other features to facilitate an understanding of this invention, all parts other than those concerned with the control and reduction of pressure, and with the course of the air from the flask 105 to the engine, being omitted; Fig. 2 is a longitudinal mid-section of the valve system provided by the present invention; Fig. 3 is a transverse section of a torpedo showing the parts in elevation, and showing the ac- 110

tual arrangement of the valve system in its relation to the adjacent and connected parts.

Referring first to Fig. 1, let A designate the shell or hull of the torpedo, B the air flask or reservoir, C the propeller screws, D the turbine or other engine, and E the propeller shaft. F is any usual starting valve. G and H are successive pressure reducing valves; J is the superheater; a b c d and e are the successive air passages whereby the air is discharged through the respective valves to the superheater and (by the pipe e) to the engine, that is, in the case of a turbine to its nozzle f.

15 The arrangement shown in Fig. 1 is partly diagrammatic, there being in a torpedo no room for such an orderly succession of parts. The arrangement shown in Fig. 3 is that which is actually used in the Bliss 20 Leavitt torpedo, and a similarly compact arrangement is required in the Whitehead or any other automobile torpedo. Fig. 3 shows the pipe a leading from the flask (not shown) to the starting valve F. This valve according to my invention is built in one structure with the reducing valves G and H, the passages b c (Fig. 1) being formed within the common shell inclosing these valves; the figure shows the passage d leading thence to the superheater J, the pipe e leading thence to the nozzle f of the turbine, and a bulkhead g inclosing the turbine and separating the after-body mechanism from that in the mid-section of the torpedo. This figure does not show the fuel pot, the water flask and their connections, nor any steering mechanism, all of which parts are packed closely within the mid-section of the torpedo.

40 Referring to Fig. 2, the preferred construction introduced by the present invention will be described. An inclosing shell K, preferably integral, is provided for the starting valve F and the reducing valves G and H. The starting valve is of well known construction, comprising a piston tappet h normally seating against a seat i to which it is pressed by a light spring j. Its piston body works freely in a cylindrical cavity k in the shell, which forms a chamber behind the piston, communicating through a port l with a controlling valve (not shown) by the opening or closing of which (which in practice is performed by the starting hook) the 45 escape of pressure from the chamber k is controlled. Before starting, with the parts in the position shown, the high pressure communicates from the inlet a' through a leak-duct m to the chamber k in which the same pressure exists, the escape through the port l being prevented by the closed control valve; hence the piston tappet is pressed to its seat with a force equal to the area of the tappet in contact with the seat, multiplied by the initial pressure. On opening the

control valve, the pressure in k rapidly blows out, so that the high pressure on the opposite side of the piston h forces it back against its spring, thereby opening the starting valve and holding it open so long as a free escape is afforded through the control port l; this being the condition which is maintained during the run. This construction of starting valve is well known and forms specifically no part of the present invention. Within the seat i is an opening b which forms the passage (b in Fig. 1) communicating between the starting valve F and the reducing valve G. This passage terminates in another seat n against which 70 closes a tappet p forming part of the primary reducing valve G. The tappet p is carried on a hollow stem q which has fastened on it a piston r moving in a cylindrical chamber s with a spring t confined in this 75 chamber and pressing against the head r in the direction tending to unseat the tappet p. Behind the piston is a chamber s' which communicates through a duct q' with the passage b. Hence when the starting valve 80 is opened the full pressure of air is quickly transmitted through this duct q' to the chamber s', where it acts against the piston r in opposition to the spring t. The piston r presents a somewhat larger area to the air 85 than that presented by the tappet p; hence the effect of the air pressure is to hold the tappet to its seat, and to this is added the pressure against the tappet of the air in the passage c on the opposite side of the tappet 90 (say 600 pounds per square inch) multiplied by the annular area of the tappet outside its stem; to these pressures tending to close the valve is opposed the stress of the spring t 95 tending to open it. In operation, when the 100 pressure on the outlet side (in passage e) falls below that for which the valve is proportioned (say 600 pounds) the stress of the spring predominates and opens the valve; upon the pressure in c exceeding the 105 predetermined pressure, this excessive pressure acting against the back of the tappet, 110 closes it to or toward its seat; hence in action the reducing valve G adjusts itself to 115 such opening as will permit a flow past it just sufficient to maintain the prescribed pressure of for example 600 pounds per square inch. This is the well understood operation of partially balanced reducing valves of this character. The reducing valve H which effects the final reduction, is 120 in general of known construction, and differs from similar valves heretofore used in practice only in that it is proportioned to effect a much smaller reduction in pressure than heretofore. In the example shown it reduces the pressure from say 600 pounds in the passage c to say 450 pounds in the passage d leading from it to the superheater. 125 As shown, it is constructed with a tappet u 130

closing against the outlet side of the seat *v* and carried on a rod or stem *u'* which carries also a plunger *w* of slightly greater area than the seat *v*, so that the air pressure in *c* tends to close the tappet to its seat. The stem *u'* projects into a spring chamber *x* in which is a spring *y* which acts against the stem (or as shown against the plunger *w*) in direction to tend to press the valve open. This pressure is adjustable by means of a screw *z* which may be set in more or less to force inwardly the plunger or abutment *y'* against which the spring reacts. The adjustment of the screw *z* determines the final pressure in passage *d* and hence determines the speed of the torpedo. As some air pressure is liable to leak into the spring chambers *s* and *x*, which would interfere with the balance of the respective valves, these chambers are vented through ports *t'* and *x'* respectively. It will be understood that by arranging the primary reducing valve *G* close alongside the reducing valve *H* and close to the starting valve *F*, and providing one shell *K* (preferably integral) in common for these three valves, I attain a degree of compactness which for the first time has rendered possible the use of two successive reducing valves in the restricted space available within the torpedo. At the same time the additional weight is so trifling as to be well within the limits of practicability. Both the valves *G* and *H* in their operative elements and mode of action, are of known type and construction; and the construction of these valves may be greatly varied, or may be substituted by other or equivalent constructions, without departing from the present invention. The invention may also be modified in other ways, as will be apparent or as may be necessitated by the specific construction and arrangement of the other parts of the torpedo.

45 I claim as my invention:—

1. A valve group for an automobile torpedo comprising a starting valve, and two successive reducing valves, said starting

valve and the primary reducing valve having tappet members engaging seats on opposite sides of an opening. 50

2. A valve group for an automobile torpedo comprising a starting valve, and two successive reducing valves, said starting valve and the primary reducing valve having tappet members engaging seats on opposite sides of an opening, and having their members controlling such tappet members extended in contrary directions to opposite sides of said opening. 55

3. A valve group for an automobile torpedo comprising a starting valve, and two successive reducing valves, said starting valve and the primary reducing valve having tappet members engaging seats on opposite sides of an opening, and said reducing valve comprising a stem carrying said tappet having a balancing piston on said stem, a cylinder in which said piston moves, the chamber on one side of said piston having a passage communicating with the high pressure side of the valve to admit pressure thereto tending to close the tappet, and a spring tending to open the tappet. 60

4. A valve group for an automobile torpedo comprising a starting valve, and two successive reducing valves, said starting valve and the primary reducing valve having tappet members engaging seats on opposite sides of an opening, and said primary reducing valve comprising a stem carrying said tappet, a piston on said stem, a cylinder in which said piston moves, said stem having a passage through it admitting high pressure air to said cylinder on the remote side of said piston to establish a pressure therein tending to close the tappet, and a spring in said cylinder pressing against said piston and tending to open the tappet. 75

In witness whereof, I have hereunto signed my name in the presence of two subscribing witnesses.

WILLIAM DIETER.
